UNITED STATES PATENT OFFICE.

ALFRED WILLIAM CHRIST, OF CHICAGO, ILLINOIS.

ROLL-RETAINING DEVICE.

Application filed December 16, 1920. Serial No. 431,193.

To all whom it may concern:

Be it known that I, ALFRED WILLIAM CHRIST, a citizen of the United States, and a resident of the city of Chicago, county of Cook, and State of Illinois, have invented certain new and useful Improvements in Roll-Retaining Devices, of which the following is a specification.

My invention relates to an improvement in a roll retaining device, and has for its object the provision of means which will prevent a roll placed in a case or container from unrolling.

Other objects will appear hereinafter.

The invention consists in the combinations and arrangements of parts hereinafter described and claimed.

The invention will be best understood by reference to the accompanying drawings forming a part of this specification, and in which,

Fig. 1 is a plan view showing my invention applied to a music roll box and roll therein;

Fig. 2 is a vertical sectional view thereof;

Fig. 3 is a fragmentary elevational view showing the clamp attached to the side of the box;

Fig. 4 shows a modified form of the device applied to a box and roll shown in cross-section; and

Fig. 5 shows a blank from which the spring clamp is formed.

My invention is shown in connection with a case or container 10 in the form of a music roll box, containing a music roll 11, the outer part or flap 12 of which is pressed upon by the resilient clamp member 13, retaining the roll in position and preventing the same from unrolling.

The preferred form of clamp member consists of a resilient blank of any suitable material, such as brass, and comprises a body portion and an arm 14 extending laterally from one end thereof, bent or curved upon itself toward said body portion, as at 15, near the points of connection with said body portion. Cleats 16 are provided at the corners of the body portion which are bent at

right angles therefrom and pass through a side wall of the container, and may be bent over on the outside of the wall of said container if desired.

In Figs. 1 and 2 the clamping member is shown applied to one side of the music box, in full lines, but the clamp may be used on

the other side, as shown in dotted lines in said figures, or a clamp may be placed on both sides of the box.

Fig. 4 illustrates a modified form in which the body portion 13' is provided with two arms 14' extending at right angles from the two ends of said portion, passing up along the sides of the box, and being bent or curved back upon themselves near their middle portions, as at 15'. Cleats 16' extend from the body portion and pass through the bottom of the box instead of the side, as in the preferred form.

Although my invention has been illustrated in connection with a music roll box and roll, the resilient clamp may be used in connection with any form of roll container or case, and in view of its resilient arm or arms bearing against the roll is adapted to retain said roll in position and prevent unrolling thereof.

While I have illustrated and described the preferred form of construction for carrying my invention into effect, this is capable of variation and modification without departing from the spirit of the invention. I, therefore, do not wish to be limited to the precise details of the construction set forth, but desire to avail myself of such variations and modifications as come within the scope of the appended claims.

Having described my invention, what I claim as new and desire to secure by Letters Patent, is:—

1. A member provided with a body portion, a resilient arm bent back toward and extending alongside a part of said body portion, and means upon said body portion for attaching said member to a wall of a case with said part engaging said wall, said member being adapted to prevent a roll from unrolling in said case by exerting pressure between said wall and roll, substantially as described.

2. A member comprising a body portion, a resilient arm extending from and bent back toward said body portion, and cleats extending from said body portion by means of which said member is mountable in a case with said body portion engaging the wall of said case, said arm being adapted to bear resiliently against a roll in said case and prevents said roll from unrolling, substantially as described.

3. A member provided with a body portion, a plurality of resilient arms extend-

ing at right angles from said body portion, each of said arms being bent upon itself towards said body portion, said member being mountable in a case to engage the inner 5 wall thereof and capable of preventing a roll from unrolling in said case by bearing between said walls and roll, substantially as described.

4. The combination with a music roll case, 10 of a roll retaining device comprising a metallic strap; a resilient arm extending from each end of and bent back toward said strap, said arms being adapted to bear resiliently

between the sides of said case and a music roll in said case to prevent said roll from 15 unrolling, and means extending from each end of said strap for detachably mounting said device in said case; substantially as described.

In testimony whereof I have signed my 20 name to this specification in the presence of two subscribing witnesses.

ALFRED WILLIAM CHRIST.
